C. E. TREAT

SWITCH

Filed May 31, 1922

INVENTOR
CLIFFORD E. TREAT
Your *Attorneys*

UNITED STATES PATENT OFFICE.

CLIFFORD E. TREAT, OF LOS ANGELES, CALIFORNIA.

SWITCH.

Application filed May 31, 1922. Serial No. 564,309.

To all whom it may concern:

Be it known that I, CLIFFORD E. TREAT, a citizen of the United States, and a resident of the city of Los Angeles, county of Los Angeles, and State of California, have invented certain new and useful Improvements in Switches, of which the following is a specification.

This invention relates to electric switches 10 and particularly to electric switches than can be readily embodied in an electrical attachment plug.

An important object of my invention is to provide a switch that is small and compact 15 in character.

Another object of my invention is to provide a switch exceptionally positive in action. The switch in my invention is held firmly in place either in the open or closed 20 position. This is an important feature of my invention, especially when the switch is combined in an attachment plug. Such attachment plugs receive considerable rough handling.

Another object of my invention is to provide a switch which does not require a coiled spring to impart resistance to the opening or closing of the switch to maintain the movable contact in its proper position.

Another object of my invention is to provide an electrical attachment plug with a switch, the members of which can be easily mounted and held in position independent of the containing case.

The accompanying drawings illustrate the invention:

Figure 1 is a side elevation of a switch constructed in accordance with the provisions of this invention. The switch in this 40 instance being embodied in an electrically equipped attachment plug.

Fig. 2 is a side elevation of Fig. 1 with half the case removed to show the construction of the switch.

Fig. 3 is a side elevation of half the case.

Fig. 4 is an edge elevation of Fig. 2 sectioned along the irregular line x^4-x^4 .

Fig. 5 is an edge elevation of Fig. 2 sectioned along the line x^5-x^5 .

Fig. 6 is an edge elevation of Fig. 2 sectioned along the irregular line x^6-x^6 .

Fig. 7 is an elevation of the switch mechanism with the switch open.

Fig. 8 is an elevation of the switch mechanism with the switch closed.

Referring to the drawings, there is pro-

vided a suitable case in this instance substantially in duplicate halves or sections 1.

The longitudinal edge walls 2 of the case are provided with openings 3 to accommodate an operating member 4. The ends 5 of the operating member 4 are circular in cross section and composed of insulating material. The intermediate portion 6 of the operating member 4 is composed of spring metal. The 60 spring metal is bent near the center to form a loop or projecting surface 7. A guide member 8 holds the operating member 4 in place by means of guides 9. In this case the guide member 8 contains also a pin 10 which holds a pivotally mounted contact member 11 and a roller 12. The pin 10 is so placed 65 on the guide member 8 that the pivotally mounted contact member 11 and roller 12 are engaged by the projecting surface 7 of the 70 operating member 4.

Figs. 7 and 8 illustrate the action of the switch mechanism. When the switch is either open or closed, there is little or no tension on the spring 6. The operating 75 member 4 is held stationary by the contact of the projecting surface 7 with the roller 12 on one side and the pivotally mounted contact member 11 on the other. The contact member 11 is held in position by the contact of one of its edges 13 against the spring 6. When the operating member 4 is moved the projecting surface 7 of the operating member 4 is pushed down by the roller 12 and the spring 6 is pushed down 90 against the guides 9. The spring 6 of the operating member 4 yields to permit the projecting surface 7 to pass under the roller 12. (Fig. 7.) A resistance is imparted 95 thereby to the operation of the switch. This resistance is equally encountered whether the switch is being opened or closed. The pivotally mounted contact member 11 is operated to open or close the switch by the action of the projecting surface 7 of the operating member 4 engaging in a notch 24 formed in the pivotally mounted contact member 11.

The guide member 8 to which the pivotally mounted contact member 11 and roller 12 are loosely fastened by the pin 10 and which holds the operating member 4 by the guides 9 is fastened on an insulating mounting member 14. On the mounting member 14 is fastened a stationary contact member 15. The stationary contact member 15 is 105 provided with a screw 16 for connection with the electric supply and for binding the 110

contact member 15 to the mounting member 14. The contact faces 17 of the contact member 15 are sprung together when the switch is open (Fig. 7). The pivotally mounted contact member 11 is wedged between the faces 17 of the stationary contact member 15 when the switch is closed. The wedging of the pivotally mounted contact member 11 between the faces 17 of the stationary contact member 15 insures excellent contact between the faces 17 and the pivotally mounted contact member 11. The guiding member 8 in this case holds a pin 18 by which the plug receptacle 19 is connected.

15 The parts above mentioned constitute the switch proper. In this particular embodiment of the invention, I have provided a second terminal in the form of a plug receptacle 20, a duplicate of the plug receptacle 19. Connected with the plug receptacle 20 is provided a clip 21 containing a binding screw 22, whereby an electric cord 23 is attached to the clip 21.

It is clear from the foregoing that the 25 construction above described provides a plug receptacle which may readily be attached to an electric heating or cooking device and that the electric current may be readily opened or closed by means of the operating member 4. While the particular construction 30 illustrated in the foregoing description and accompanying drawings is well suited to the purposes of my invention, it is to be understood that such construction has been 35 set forth as one example only of a practical embodiment of my invention. My invention is not limited to the single embodiment above mentioned but is of the scope set forth in the following claims.

40 I claim:

1. In a switch the combination of an operating member comprised of a spring having a projecting surface, a guide member limiting said operating member to a relatively 45 reciprocating motion, and a roller spaced to engage said projecting surface to place tension on said operating member when reciprocated to open or close the switch.

2. In a switch the combination of an operating member comprised of a spring having a projecting surface, a guide member limiting said operating member to a relatively

reciprocating motion, a roller spaced to engage said projecting surface to place tension on said operating member when reciprocated to open or close the switch, a stationary contact member, and a pivotally mounted contact member adapted to releasably engage said stationary contact member by the reciprocating action of said projecting surface.

3. In a switch the combination of an operating member comprised of a spring having a projecting surface, a guide member limiting said operating member to a relatively 65 reciprocating motion, a roller spaced to engage said projecting surface to place tension on said operating member when reciprocated to open or close the switch, a stationary contact member, a pivotally mounted contact 70 member adapted to releasably engage said stationary contact member by the reciprocating action of said projecting surface, an insulating mounting member holding in spaced relation the aforesaid members of the 75 switch.

4. In a switch equipped attachment plug, the combination of a case, a reciprocating operating member comprised of a spring having a projecting surface, a guide member 80 limiting said operating member to relatively reciprocating motion, a roller spaced to engage said projecting surface to place tension on said operating member when reciprocated to open or close the switch.

5. In a switch equipped attachment plug, the combination of a case, an operating member comprised of a spring having a projecting surface, a guide member to hold said operating member to a relatively reciprocating motion, a roller placed to engage said projecting surface to provide a tension on said operating member when reciprocated to close the switch, a stationary contact member, a pivotally mounted contact member adapted to releasably engage the first contact member upon reciprocation of said operating member.

Signed at Los Angeles, California, this 17th day of May, 1922.

CLIFFORD E. TREAT.
